Primary Examiner — Darlington Ly(74) *Attorney, Agent, or Firm* — Procopio, Cory, Hargreaves & Savitch LLP(57) **CLAIM**

The ornamental design for a hub system for bicycle wheel, as shown and described.

DESCRIPTION

FIG. 1 is a front perspective view of a hub system for bicycle wheel showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an exploded perspective view thereof.

The broken lines in the drawings illustrate portions of the hub system for bicycle wheel that form no part of the claimed design.
